UNITED STATES PATENT OFFICE.

HENRY H. CUTLER, OF BROOKLINE, MASSACHUSETTS.

FORCE-FEED CHARGE-FORMING DEVICE.

Application filed December 27, 1923. Serial No. 682,962.

The object of my invention is to produce a force-feed charge-forming device that will deliver to the intake manifold an exceedingly intimate mixture of air and fuel in 5 a correct and uniform proportion, and surround each minute particle of fuel with sufficient air to make it possible to produce, when fired, complete combustion or CO_2 , which is a harmless, non-poisonous gas.

10 This I accomplish chiefly by forcing the liquid fuel under pressure around the periphery of a comparatively large valve lifted only a few thousandths of an inch from its seat. For example, this distance in a one 15 inch carburetor may be about .002 of an inch. The style of carburetor which has gone almost into universal use sucks the fuel around the surface of a needle valve lifted from its seat a distance frequently of $1/50$ or .02 of an inch, 20 thus delivering the fuel to the mixing chamber in the shape of globules averaging .02" in diameter, or one thousand times the volume of drops .002 inches in diameter obtained in my invention.

25 It has been ascertained experimentally that the large drops of liquid fuel produced in most carburetors hold to their globular form with great tenacity.

This means that only the outside circumference of these comparatively large drops of 30 liquid fuel come in contact with the air from which they may derive sufficient oxygen to form CO_2 gas when fired, the inside or greater part of these globules not coming in direct contact with the air, cannot obtain sufficient oxygen to form CO_2 , with the result 35 that the exhaust gases of all gasoline engines universally used for propelling automobiles, emit CO gas with the exhaust, which is highly poisonous, besides causing a great loss 40 in the efficiency of the engine.

The drawings submitted are made full size for a so called one inch carburetor and while this design may be used in connection with 45 an engine having any number of cylinders, it is better, and especially adapted for a four cylinder engine.

Fig. 1 is a top plan view of a complete charge-forming device embodying my invention;

50 Fig. 2 is a vertical cross section through the middle of a complete charge-forming device on line 2—2 of Fig. 1;

Fig. 3 is a vertical cross section through 55 the middle taken at right angle to Fig. 2 on line 3—3 thereof;

Fig. 4 is a horizontal section on line 4—4 of Fig. 3;

Fig. 5 is a vertical section on line 5—5 of Fig. 3;

Fig. 6 is a vertical section on line 6—6 of Fig. 2;

Fig. 7 is a horizontal section on line 7—7 of Fig. 2;

Fig. 8 is a top plan view of the steering 65 post and control levers of an automobile;

Fig. 9 is a horizontal section on line 9—9 of Fig. 2.

Fig. 10 is an elevation partly in section of the front or number one cylinder of a four 70 cylinder, four cycle engine, having the so-called T head, and showing applicant's charge-forming device attached thereto.

My charge-forming device consists of a main casting 10, cylindrical in shape, tapering gradually towards the top, and provided there with a flange 11 adapted to be bolted to the intake manifold of the engine. Two projecting lugs 12, 12, serve to hold the outside bearing casting 13 to the bowl 10 by 80 means of four screws 14, 14.

The cylinder or bowl 10 is turned out smooth inside at 15, 15 and 16, 16 and a bottom casting 17 is turned up to fit tightly in the bottom of the bowl 10 to which it is 85 fastened by the screws 18, Fig. 4.

The bottom casting 17 has a downward projecting lug 19 which is connected with the outside bearing casting 13 by a metal bar 20 which serves to hold the castings 10 and 13 rigidly together.

The inside of the bottom casting 17 is turned out to fit a steel cylinder 21, which is threaded on the inside and held in place by the set screw 22. Screwed into this cylinder 95 21 is a large distributing valve 23 which takes the place of the needle valve in most carburetors. This valve 23 is ground accurately on to a seat formed in the bottom casting 17, and is then partially unscrewed sufficiently to lift it from its seat a few thousandths of an inch. The distributing valve 23 is fastened with screws 24 to a double conical casting 25. Underneath the valve 23 is a small cylindrical reservoir 26, designed to hold a 100 small amount of the liquid fuel.

Three circular openings 27, Figs. 2 and 4, are cast through the top of the bottom casting 17, which openings connect with a passageway 28 which can be opened and closed 110 to any desired amount by means of the butterfly valve 29 operated by the crank 30.

Another conical casting 31 is also inserted inside the bowl 10, so as to keep the area of the air passageway the same from the time the air enters through the butterfly valve 29 until it reaches the intake manifold through the circular opening 29' in the flange 11. It is thus seen that the suction of the engine will draw the air through the butterfly valve 29, into the passageway 28, thence 10 through the arc-shaped openings 27, and will finally enter the mixing chamber 32 as a hollow cylinder of air with a very thin wall, shown in the drawings as 3/16 of an inch and tapering to 3/32" near the top of the mixing chamber.

The liquid fuel enters the reservoir 26 through two holes 33, 33, drilled through the bowl 10 and bottom casting 17, after these two castings have been screwed together.

The fuel is forced into the reservoir 26 and thence by the valve 23 into the mixing chamber 32 by means of a pair of plunger pumps 34, 34, whose stroke is varied according to the load on the engine.

The pump plungers are driven by a walking beam 35, fastened rigidly to a long hub casting 36, free to turn on the shaft 37, which is supported at each end by the bowl 30 10 and the outside bearing casting 13 respectively. Connecting rods 38, 38 connect the pump plungers and walking beam. The hub casting 36 has a slotted arm 39 projecting at right angles. A square steel block 40 35 slides freely in this slot, and is held by a pin 41, on which it is free to oscillate. The other end of the pin 41 is fastened rigidly to a forked lever 42 by means of the nuts 43, but can be slid up and down in the slot 44, and 40 thereby adjusted so as to vary over a wide range the swing of the walking beam 35 and stroke of the plungers 34.

The forked lever 42 is rigidly secured to a hub 45, free to oscillate on a pin 46, and is 45 given a pendulum movement by means of the disc 47, Figs. 2 and 6, which is fastened by a pin 48 to a shaft 49 driven from the engine shaft at preferably the same speed by means of the sprocket wheels 50, 50' and chain 50".

50 The eccentric disc 47 is shown in the drawings as occupying a concentric position with the driving shaft 49, in which position the rotation of the shaft 49 will not cause the forked lever 42 to oscillate and there will be 55 no movement of the walking beam 35 or pump plungers 34.

The mechanical center of the disc 47, however, can be moved away from the center of the driving shaft 49 by means of the cylindrical sliding eccentric 51, which has a hole 51' drilled through it at an angle with its central axis, so that it can slide freely on the shaft 49, and also through a hole 47' in the eccentric disc 47 drilled at the same angle 65 and size of the outside diameter of the ec-

centric 51. A slot 52, the same thickness as the pin 48, is milled nearly through the cylinder 51, and then its open end may be closed up with the electric pencil or otherwise. This cylinder 51 while free to slide on the 70 shaft 49, is compelled to rotate with it, without changing its relative angular position, by means of the pin 48.

It is now seen that as the cylinder 51 is slid along the shaft 49, it will force the mechanical center of the disc 47 farther and farther away from the center of the shaft 49, thereby increasing its eccentricity and setting up a pendulum movement of the forked lever 42 and starting the desired degree of motion of the walking beam 35 and pump plungers 34.

The movement of the cylinder 51 is controlled by the carriage 53 which also slides freely on the shaft 49 as well as on the bar 20 which it embraces and which holds it from rotation.

The carriage 53 is fastened to a sliding rod 54 which may be connected with the throttle lever of an automobile by means of the usual system of rods and levers, thus giving the operator complete control of the amount of fuel fed to the engine.

The fuel supply enters the intake valve chambers of the two plunger pumps at 62 95 whence it is drawn through the inlet valves 63 into the pump barrel, thence through the outlet valve 65, passage 33, reservoir 26, around the circumference of the distributing valve 23 into the mixing chamber 32, which 100 it enters in the shape of an extremely thin hollow cone, with walls only a few thousandths of an inch thick. Here it is met by a hollow cylinder of air with also a very thin wall, so that the extremely small globules 105 of fuel become thoroughly mixed with the air before being brought together in a solid stream at the neck of the carburetor when the complete mixture enters the intake manifold of the engine.

In order to adjust the degree of opening of the distributing valve 23, a number of holes 25' are first drilled and tapped, close together in the side of the conical casting 25; the valve 23 is then unscrewed from its seat the 115 desired amount and a threaded rod 55 is pushed up through a slot 55' (Fig. 8) in the bottom of the bowl 10, and then screwed into the proper hole in the cone 25. The end of the rod 55 is then attached to a spring 56 120 which is fastened at 57 and tends to, as shown in the drawings, open the valve 23 still wider, but is prevented from doing this by the triangular piece 58 (Fig. 9) against which it presses. Since the triangular piece 58 is fastened by the screws 59 to the sliding carriage 53, it will now be plain that as the carriage 53 is moved back and forth, the cone 25 and valve 23 will be made to oscillate back and forth and thus detach any grain of dust or 130

foreign matter that might otherwise tend to stop up a portion of the very narrow passage between the valve 23 and its seat.

The inlet valves 63 are shown mechanically operated by means of the bell cranks 68, (Fig. 3) pivoted at 69, operated by valve tappets 70, driven by the cam 71, pinned to the driving shaft 49. A minute air chamber 75 is drilled into the top projection of the distributing valve 23 and communicates with the reservoir 26 by the passage 75'. The volume of this air chamber can be regulated by the long screw 76.

An electrical heating coil 77 surrounds this upward projection of the valve 23 with its insulated lead 77' connected with an insulated binding post 78 in the neck of the carburetor bowl 10. The top and bottom of the valve 23 are also shown faced with mica 78' in order to help throw the heat derived from the heating coil towards the circumference of the valve 23 where it warms more or less the fuel being forced between this valve 23 and its seat.

In all four cylinder four cycle combustion engines there is a steady pulsating suction action in the intake manifold varying from practically nothing to a maximum when one of the engine's pistons starts on its intake stroke until it reaches about the middle of the stroke. The velocity and amount of air being drawn into the intake manifold varies accordingly as does also the amount of fuel sucked in by the air rushing through the ordinary type of carburetor.

In order to duplicate this necessary action I drive the two pumps shown at the same speed as the engine and also synchronize the movement of the plungers with the pistons of the engine. Thus when an engine piston starts on its suction stroke one of the two pumps starts on its delivery stroke, and thus automatically increases the amount of fuel pumped in precisely the same proportion and time that the amount of air is increased, thereby keeping constant the percentage of air and fuel during all portions of the suction stroke of the engine. In a Diesel engine the pumps force in fuel during the power stroke, and stop this action long before the engine piston reaches the end of its power stroke and consequently do not operate in synchronism with the engine pistons.

It is now evident that my charge-forming device produces not only an exceedingly intimate mixture of air and fuel, but also breaks up the fuel into exceedingly small globules constituting a genuine mist. It also supplies electrical heat at the proper place to assist this mist in becoming a gas before it is fired, and furthermore, when used in connection with a four cylinder engine, keeps an absolutely constant percentage of mixture during all portions of a suction stroke of the engine.

The resulting effect is the complete combus-

tion of the fuel into CO_2 , a non-poisonous gas.

It is furthermore practical to operate an ordinary engine over wide ranges of load at constant compression by varying the stroke of the pumps and consequently the amount of fuel supplied, without cutting down the supply of air, as is done in the Diesel engine. To accomplish this when using the type of engine ordinarily used by propelling automobiles, I utilize the two levers 79, 80 shown in Fig. 8 which it is customary to supply with most automobiles, by first disconnecting said levers from their normal attachments, i. e., the timer and throttle, and then attach the butterfly valve 29 to the system of rods and levers already installed leading to the spark lever 79, and connect the throttle lever 80 to the sliding carriage 53, thus giving the operator complete control of both the air and fuel supply.

Fig. 8 shows a slight change in the construction of the throttle lever, in order to compel the operator to change the compression when the engine is idling or running under very light loads, the rack 81 of the lever 79 being attached to and movable with the lever 80, so that by moving the lever 80, the lever 79 also is moved, and the butterfly valve 28 operated simultaneously with the carriage 53.

When my charge-forming device is used on a stationary engine running at constant speed under the control of a governor, it is only necessary to connect the governor rod with the sliding carriage rod 54, adjust the butterfly valve 29 in a permanent position and run the engine under constant compression.

Before the charge-forming device is put to work it is necessary to press open both the inlet valve 63 and the air relief valve 67 on each pump. The fuel will then flow in through the inlet valve 63 and drive out all the air through the air relief valve 67, thus completely filling the valve chamber and pump cylinder with the liquid fuel.

It is furthermore necessary to make the area of the opening of the distributor valve 23 a trifle smaller than the area of the plunger 34, in order to accumulate a slight pressure in the reservoir 26 and thus cause the fuel to spray entirely around the circumference of the distributor valve 23. This pressure will cause a very small amount of fuel to back up into the air reservoir 75 which will then be forced out by the compressed air after the plunger has finished its delivery stroke.

Now since the flow of liquid fuel is apt to be sluggish in getting started into the pump when its plunger starts on its suction stroke, I may set the pump plungers slightly in advance of the engine pistons and regulate the size of the air reservoir 75 with the screw 76, to compensate for the inertia effect of the liquid fuel.

The top part of Fig. 10 shows a vertical

section through the middle of the first cylinder of a four cylinder engine. The engine piston 93 is shown at top dead center with the connecting rod 91 vertical, the intake valve 94 about to open and the exhaust valve 95 about to close, so that the piston 93 is about to start into the cylinder on its suction stroke. The crank shaft 85, crank pin 90 and the piston pin 92 are consequently approximately in line, as shown.

My charge-forming device is shown bolted to the intake manifold 96 of the engine by means of the flange 97 in the usual manner. The shaft 49 of my charge-forming device is shown extended so as to reach to the front part of the engine. The shaft 49 of my charge-forming device is rotated at precisely the same speed as the crank shaft 85 of the engine. The two eccentrics 47 and 51 rotated by the shaft 49 and fully illustrated and described in the specification and drawings are drawn so as to throw the rocking forked lever 42 to its extreme position, thereby tilting the walking beam 35 to its extreme position so that the pump plunger 34 will have entirely completed its delivery stroke and pump plunger 34' will be just about to start on its delivery stroke.

Assuming that the engine is running and firing 1, 3, 4, 2, the intake valve of No. 2 cylinder will now be nearly wide open and the air will be still rushing through this valve, although the piston in No. 2 cylinder will have fully completed its suction stroke. The fuel pump 34 has also entirely completed its delivery stroke but during this action it has compressed the air in air chamber 75' (Fig. 2) underneath the distributing valve 23, thereby causing fuel to be forced through said valve 23 into the mixing chamber 32, thereby supplying fuel to mix with the air now rushing into No. 2 cylinder.

Now, as the piston 93 in No. 1 cylinder starts in on its suction stroke, the pump plunger 31' of my charge-forming device starts to deliver fuel underneath the distributing valve 23 and also to help maintain the pressure of the air in the air chamber 75. A supply of fuel is thus ensured to mix with the air at all times during the operation of the engine. The chief advantage claimed in using my charge-forming device over the usual form of suction-type carburetor is that by using mechanical power to force the fuel around the periphery of my distributing valve 23, it becomes practical to hold this valve 23 a distance of only one or two thousandths of an inch from its seat, thereby forcibly breaking up the fuel into a mist containing drops of fuel very much smaller than is possible when using only the suction pull of the engine cylinder, as is now the usual custom in all commercial types of carburetor.

The advantage of breaking up the fuel into extremely fine mist is well understood by all

those skilled in the art of designing carburetors. Heavy grades of fuel not capable of self-evaporating into a gas may also be used with my charge-forming device. It is evident that in the design submitted in the drawings and specification unless the valve 23 is lifted an extremely small distance from its seat the fuel from the pumps 34, 34' will flow freely through and by the valve 23, so that little or no compressed air will be stored up in the air chamber 75. Such an adjustment would not only defeat the chief object of my invention, but would cause an intermittent supply of fuel to be delivered to the engine, thereby failing to keep up the proper proportion of air and fuel which is the sole function of all practical carburetors.

In adapting my invention to a six cylinder engine I set the plungers so they will start to pump when the demand for fuel is at a minimum, and by enlarging the air reservoir 75 still further, utilize the accumulated pressure in the air reservoir to supply fuel when neither pump is delivering. This arrangement however only approximates the requirements of the engine, and in order to make my charge-forming device ideal for a six cylinder engine there should be three pumps set 120° apart, which requires a different design from the drawings submitted. With a four cylinder engine practically perfect accuracy in obtaining a uniform mixture can be obtained, however, with my invention.

Having thus described an illustrative embodiment of my invention without however limiting the same thereto, what I claim and desire to secure by Letters Patent is:—

1. A force-feed charge-forming device for supplying fuel to an internal combustion engine comprising in combination a fuel feed pump, said pump operating in synchronism with the power piston of the internal combustion engine to which said device is attached and being so timed that the delivery stroke thereof begins and ends simultaneously with the beginning and ending of the engine suction stroke, a reservoir containing a small amount of fuel relative to the capacity of said pump and subjected to the pressure of a confined gas, and a distributor valve spaced such a small distance from its seat as to oppose the flow of fuel forced through said valve by said pump and thereby cause the fuel to be forced into said reservoir for the purpose of keeping up the supply of fuel forced through said distributor valve after the completion of the delivery stroke of said pump, whereby the percentage of air and fuel is maintained constant for the entire duration of the engine intake period.

2. In combination with an internal combustion engine having a plurality of power pistons, a plurality of fuel pumps driven in mechanical synchronism with the respective power pistons of said engine and each being

so timed that the delivery stroke of each of said pumps begins and ends with the beginning and ending of the suction stroke of the corresponding power piston, a fuel reservoir of relatively small capacity communicating with said pumps and a valve for said reservoir spaced a relatively short distance from its seat.

3. The combination with an internal combustion engine having a power piston, of a fuel pump driven in mechanical synchronism with said power piston and being so timed that the delivery stroke of said pump begins and ends with the beginning and ending of

the suction stroke of said power piston, a fuel reservoir, a valve for said reservoir, the area of the opening of said valve being smaller than the area of the plunger of said pump, and an air reservoir communicating with said fuel reservoir and adapted to receive a small amount of fuel therefrom during the delivery stroke of said pump, and to deliver the same after the completion of said delivery stroke.

In testimony whereof, I have hereunto subscribed my name this 21st day of December, 1923.

HENRY H. CUTLER.
